UNITED STATES PATENT OFFICE.

GUSTAV BAUM AND JULIUS MÜLLER, OF BERLIN, GERMANY.

ALBUM.

SPECIFICATION forming part of Letters Patent No. 472,470, dated April 5, 1892.

Application filed November 28, 1891. Serial No. 413,409. (No model.)

To all whom it may concern:

Be it known that we, GUSTAV BAUM and JULIUS MÜLLER, both subjects of the King of Prussia, and both residing at Berlin, in the 5 Kingdom of Prussia, German Empire, have invented a new and useful Album with a Device for Giving it an Inclined Position, of which the following is a specification.

The desire of the beholders of albums to 10 have the same before them in a similar manner as the painting stands on the easel before the painter has already caused the makers of albums to provide the back cover with a plate-shaped support and to have the back of the 15 album below, so that the front cover and the leaves after turning lie flat on the table.

The present improvement, represented in 20 total view in the annexed drawing, has the advantage not hitherto attained that after the turning of the leaves the photographs of the rear side *r* not only lie in the same inclined position as those of the front side, but also precisely in the same distance from the eye of the beholder. This purpose is accom-

plished by a simultaneous arrangement of 25 supports *s* at the front cover *v*, as well as at the rear cover *h*, which supports are hinge fashion and connected with their appurtenant cover, so that when the book is closed they are turned into recesses of the covers. Neither 30 the sole arrangement of a support at the rear cover nor the sole arrangement of a support at the front cover is claimed; but

What is claimed, and desired to be secured by Letters Patent of the United States, is— 35

In an album, the combination, with the covers thereof, of two supports *s* *s*, permanently connected to said covers and arranged to open and hold the album in an inclined position, substantially as described. 40

In testimony whereof we have hereunto set our hands in the presence of two subscribing witnesses.

GUSTAV BAUM.
JULIUS MÜLLER.
